DIMPLE PATTERNS FOR GOLF BALLS

CROSS-REFERENCE TO RELATED
APPLICATIONS

The present application is a continuation-in-part of U.S. patent application Ser. No. 17/007,090, filed Aug. 31, 2020, which is a continuation-in-part of U.S. patent application Ser. No. 16/587,455, filed Sep. 30, 2019, now U.S. Pat. No. 10,758,783, the entire disclosures of which are hereby incorporated herein by reference.

FIELD OF THE INVENTION

The present invention relates to golf ball dimple patterns based on a square dipyramid, wherein the dimples are arranged within four substantially identical triangular sections on each of the two hemispheres of the ball.

BACKGROUND OF THE INVENTION

Golf ball manufacturers make substantial efforts to maximize the aerodynamic efficiency of golf balls, though they are closely controlled by golf's national governing body, the United States Golf Association (U.S.G.A.). One U.S.G.A. requirement is that golf balls have aerodynamic symmetry. Aerodynamic symmetry allows the ball to fly with a very small amount of variation no matter how the golf ball is placed on the tee or ground. In order to improve aerodynamic symmetry, many dimple patterns are based, for example, on geometric shapes, the five Platonic Solids, and the thirteen Archimedean Solids. Because the number of symmetric solid plane systems useful in designing dimple patterns is limited, it can be difficult to devise new symmetric patterns. Moreover, dimple patterns based on some geometric shapes result in less than optimal surface coverage and other disadvantageous dimple arrangements.

Thus, there is a continuing need for novel dimple patterns incorporating unique combinations of dimple properties such as size, shape, number, volume, or arrangement, in order to provide a golf ball that has distinctive characteristics.

SUMMARY OF THE INVENTION

The present invention is directed to a golf ball having a plurality of dimples arranged in a pattern defined by a square dipyramid projected on the spherical outer surface of the ball. The plurality of dimples comprises at least three different dimple diameters, including a minimum dimple diameter, a maximum dimple diameter, and at least one additional dimple diameter. The golf ball consists of two hemispheres separated by an equator. The two hemispheres have substantially identical dimple arrangements. Each hemispherical dimple arrangement consists of four triangular sections that are defined by projecting the four faces of a square pyramid onto the hemisphere, such that each of the four triangular sections is defined by a border consisting of a linear equatorial edge which corresponds to a portion of the equator of the ball and two linear side edges connecting each end of the equatorial edge to a pole of the ball. The four triangular sections of each hemisphere are substantially identical in size and dimple arrangement. The dimple arrangement within each of the four triangular sections optionally includes a shared polar dimple having a centroid that lies at the vertex of the two side edges of the section. The dimple arrangement within each of the four triangular

sections is not rotationally symmetric about the center of the section. Each of the four triangular sections can be divided into a polar region, an intermediate region, and an equatorial region. The polar region is the area of the triangular section from latitude angle 0° to latitude angle 30°, with latitude angle 0° being the pole. The intermediate region is the area of the triangular section from latitude angle 30° to latitude angle 60°. The equatorial region is the area of the triangular section from latitude angle 60° to latitude angle 90°, with latitude angle 90° being the equator. Optionally, the diameter of the shared polar dimple, if present, is not the minimum dimple diameter or the maximum dimple diameter; alternatively, the diameter of the shared polar dimple, if present, is the minimum dimple diameter.

In a particular embodiment, the polar region includes at least one non-polar dimple having the minimum dimple diameter and does not include a dimple having the maximum dimple diameter. The intermediate region includes at least one dimple having the minimum dimple diameter and at least one dimple having the maximum dimple diameter. The equatorial region includes at least one dimple having the maximum dimple diameter and does not include a dimple having the minimum dimple diameter. In a particular aspect of this embodiment, the intermediate region includes at least one dimple having the minimum dimple diameter. In another particular aspect of this embodiment, the intermediate region includes at least one dimple having the maximum dimple diameter. In another particular aspect of this embodiment, the intermediate region includes at least one dimple having the minimum dimple diameter and at least one dimple having the maximum dimple diameter.

In another particular embodiment, the polar region has a dimple surface coverage S_p , the intermediate region has a dimple surface coverage S_i , the equatorial region has a dimple surface coverage S_e , and $S_p \neq S_i \neq S_e$.

In another particular embodiment, the polar region has a dimple surface coverage S_p , the intermediate region has a dimple surface coverage S_i , the equatorial region has a dimple surface coverage S_e , and $S_i < S_p < S_e$. In a further particular aspect of this embodiment, each of the polar region, the intermediate region, and the equatorial region includes at least one dimple having the maximum dimple diameter. In another further particular aspect of this embodiment, the dimple arrangement includes a shared polar dimple, and the shared polar dimple has the minimum dimple diameter.

In another particular embodiment, from 2% to 10% of the dimples have an elliptical plan shape. In a particular aspect of this embodiment, each dimple having an elliptical plan shape is located in the polar region.

In another particular embodiment, a majority of the dimples are spherical dimples having a circular plan shape and a cross-sectional profile defined by a spherical function, the difference in the average edge angle of the spherical dimples present in the polar region and the average edge angle of the spherical dimples present in the intermediate region is greater than 0.25°, the difference in the average edge angle of the spherical dimples present in the intermediate region and the average edge angle of the spherical dimples present in the equatorial region is greater than 0.25°, and the difference in the average edge angle of the spherical dimples present in the polar region and the average edge angle of the spherical dimples present in the equatorial region is greater than 0.25°.

BRIEF DESCRIPTION OF THE DRAWINGS

In the accompanying drawings which form a part of the specification and are to be read in conjunction therewith and in which like reference numerals are used to indicate like parts in the various views:

FIG. 1 illustrates four faces of a square pyramid projected onto a hemisphere;

FIG. 2 illustrates one of the four faces of FIG. 1 divided into three regions;

FIG. 3 is a schematic diagram illustrating a method for measuring the diameter of a dimple;

FIGS. 4A-4C illustrate the face of FIG. 2 with dimples arranged therein according to an embodiment of the present invention;

FIGS. 5A-5C illustrate the face of FIG. 2 with dimples arranged therein according to an embodiment of the present invention;

FIGS. 6A-6B illustrate the face of FIG. 2 with dimples arranged therein according to an embodiment of the present invention;

FIG. 7 illustrates the face of FIG. 2 with dimples arranged therein according to an embodiment of the present invention;

FIG. 8 illustrates the face of FIG. 2 with dimples arranged therein according to an embodiment of the present invention; and

FIG. 9 illustrates the face of FIG. 2 with dimples arranged therein according to an embodiment of the present invention.

DETAILED DESCRIPTION

A square pyramid is a polyhedron formed by connecting each of the four vertices of a square base to an apex. The resulting solid consists of the square base and four triangular faces that are equal in size, and has five vertices, including the four vertices of the square base and the apex. Each of the four triangular faces has two side edges and a base edge. Adjacent faces have a common side edge. Thus, a square pyramid has eight linear edges, including four side edges and four base edges.

A square dipyramid is a polyhedron formed from two square pyramids joined at their bases. The resulting solid consists of eight triangular faces that are equal in size, and has six vertices, including four vertices of the base at which the two square pyramids are joined and the apex of each of the two square pyramids. Each of the eight triangular faces has two side edges and a base edge. Adjacent faces on the same side of the square dipyramid have a common side edge, and adjacent faces on opposite sides of the square dipyramid have a common base edge. Thus, a square dipyramid has twelve linear edges, including eight side edges and four base edges.

Golf ball dimple patterns of the present invention are based on a square dipyramid. As shown in FIG. 1, each hemisphere of the ball consists of four triangular dimple sections 10 defined by projecting the four faces of a square pyramid onto the hemisphere. Each of the four triangular dimple sections is defined by a border consisting of two linear side edges 13 and a linear equatorial edge 11 corresponding to the side edges and the base edge of a face of the square pyramid. Thus, the two hemispheres of the ball correspond to two square pyramids joined at their bases to form a square dipyramid projected onto the spherical outer surface of a golf ball. Each base edge of the square dipyramid, when projected onto the spherical outer surface of the

ball, corresponds to a portion of the equator of the ball. Each of the two apexes of the square dipyramid, when projected onto the spherical outer surface of the ball, corresponds to a pole of the ball.

5 The two hemispheres of the ball have substantially identical dimple arrangements. For purposes of the present disclosure, dimple arrangements are substantially identical if the relative positions of their dimples' centroids are about the same, as would be understood by one of ordinary skill in the art. The overall dimple pattern on the golf ball may have a rotational offset between the two hemispheres of up to 45°.

10 The dimple arrangement within each of the four triangular dimple sections on each of the two hemispheres of the ball is substantially identical. For purposes of the present disclosure, 15 the triangular section within which a dimple is located is determined based on the location of the centroid of the dimple. Thus, each dimple on the ball is said to be located in a single dimple section, other than dimples having a centroid that is located along a side edge or an equatorial edge.

20 Dimples having a centroid that is located along an edge are referred to herein as shared dimples. A shared dimple whose centroid lies on a side edge, but does not lie at one of the two apexes of the dipyramid or at one of the four vertices of the base at which the two square pyramids are joined, is referred to herein as a side edge dimple. Thus, side edge dimples are shared between adjacent sections of one hemisphere that have a common side edge on which the centroid of the side edge dimple lies. A shared dimple whose centroid 25 lies on an equatorial edge, but does not lie at one of the four vertices of the base at which the two square pyramids are joined, is referred to herein as a shared equatorial dimple. Thus, shared equatorial dimples are shared between adjacent sections of different hemispheres that have a common equatorial edge on which the centroid of the shared equatorial dimple lies. A shared dimple whose centroid lies at an apex, i.e., a single point shared by the four sections of one hemisphere and corresponding to the pole, is referred to herein 30 as a polar dimple. Thus, polar dimples are shared between the four sections of the hemisphere containing the pole on which the centroid lies. A shared dimple whose centroid lies at one of the four vertices of the base at which the two square pyramids are joined is referred to herein as a base vertex dimple. Thus, base vertex dimples are shared 35 between four sections, including two adjacent sections of one hemisphere that have common equatorial edges with two adjacent sections of the other hemisphere.

40 Dimples of the present invention are either a shared dimple or a non-shared dimple. Thus, non-shared dimples of the present invention are dimples having a centroid that is not located along an edge. Non-shared dimples of the present invention include dimples having a perimeter that is not intersected by any edge, referred to herein as non-intersected dimples, and dimples having a perimeter that is intersected by an equatorial edge but not a side edge, referred to herein as non-shared equatorial dimples. Dimple patterns of the present invention do not include non-shared dimples having a perimeter that is intersected by a side edge.

45 The dimple arrangement within each of the triangular sections comprises a plurality of non-intersected dimples, and, optionally, one or more of the following: a polar dimple, one or more side edge dimples, one or more non-shared equatorial dimples, one or more shared equatorial dimples, or one or more base vertex dimples.

50 In a particular embodiment of the present invention, the dimple arrangement within each of the triangular sections consists of a plurality of non-intersected dimples, at least

one side edge dimple, at least one non-shared equatorial dimple, and, optionally, a polar dimple. In a particular aspect of this embodiment, there are no dimple free great circles on the outer surface of the ball. In other words, in this particular aspect, every great circle on the outer surface of the ball intersects at least one dimple.

In another particular embodiment of the present invention, the dimple arrangement within each of the triangular sections consists of a plurality of non-intersected dimples, at least one non-shared equatorial dimple, and, optionally, a polar dimple. In a particular aspect of this embodiment, the triangular section includes a polar dimple, and there are no dimple free great circles on the outer surface of the ball. In another particular aspect of this embodiment, the triangular section does not include a polar dimple, and the outer surface of the ball has two dimple free great circles defined by the side edges of the triangular sections.

In another particular embodiment of the present invention, the dimple arrangement within each of the triangular sections consists of a plurality of non-intersected dimples, at least one side edge dimple, and, optionally, a polar dimple. In a particular aspect of this embodiment, the outer surface of the ball has a dimple free great circle corresponding to the equator.

In another particular embodiment of the present invention, the dimple arrangement within each of the triangular sections consists of a plurality of non-intersected dimples. In a particular aspect of this embodiment, the outer surface of the ball has a dimple free great circle corresponding to the equator and two dimple free great circles defined by the side edges of the triangular sections.

Referring again to FIG. 1, the dimple arrangement within each of the four triangular dimple sections 10 is substantially identical, such that the dimple arrangement on each hemisphere of the ball has four-way rotational symmetry about a polar axis 5. Thus, for each non-shared dimple located within a particular triangular dimple section, there is a corresponding non-shared dimple in each of the other three dimple sections of that hemisphere. For dimple patterns of the present invention that include side edge dimples, for each side edge dimple having a centroid located along a particular side edge, there is a corresponding side edge dimple located along each of the other three side edges of that hemisphere. For dimple patterns of the present invention that include shared equatorial dimples, for each shared equatorial dimple having a centroid located along a particular equatorial edge, there is a corresponding shared equatorial dimple located along each of the other three equatorial edges. For dimple patterns of the present invention that include polar dimples, a polar dimple on one hemisphere has a corresponding polar dimple on the other hemisphere. For dimple patterns of the present invention that include base vertex dimples, for each base vertex dimple having a centroid located at a particular vertex of the base at which the two square pyramids are joined, there is a corresponding base vertex dimple located at each of the other three base vertices. For each set of corresponding dimples, the relative positions of the dimple centroids within their respective sections are about the same, and, in a particular embodiment, each of the dimples within that set of corresponding dimples has substantially the same dimple characteristics (e.g., plan shape, cross-sectional shape, diameter, edge angle, etc.).

The dimple arrangement within each of the triangular sections is not rotationally symmetric about the center of the section.

Optionally, the dimple arrangement within each of the triangular sections has mirror symmetry over a plane that

intersects the polar axis and the midpoint of the linear equatorial edge of the section. In a particular embodiment, the dimple arrangement within each of the triangular sections has mirror symmetry and the centroid of at least one non-polar dimple lies on the plane of mirror symmetry. In a particular aspect of this embodiment, each non-polar dimple whose centroid lies on the plane of mirror symmetry has a diameter independently selected from the maximum dimple diameter and the second largest dimple diameter (i.e., the greatest diameter of all of the additional diameters present in the dimple pattern). In another particular aspect of this embodiment, each non-polar dimple whose centroid lies on the plane of mirror symmetry has the maximum dimple diameter.

Each of the triangular sections can be divided into three regions: a polar region, an intermediate region, and an equatorial region. The polar region is the area of the triangular section from latitude angle 0° to latitude angle 30°. The intermediate region is the area of the triangular section from latitude angle 30° to latitude angle 60°. The equatorial region is the area of the triangular section from latitude angle 60° to latitude angle 90°. Latitude angle 0° is the pole. Latitude angle 90° is the equator. For example, FIG. 2 shows one of the triangular dimple sections 10 of FIG. 1. The triangular section is divided into a polar region 15, an intermediate region 17, and an equatorial region 19.

The region within which a dimple is located is determined based on the location of the centroid of the dimple. For purposes of the present disclosure, a dimple having a centroid located at a latitude angle of less than 28° is defined as being within the polar region; a dimple having a centroid located at a latitude angle of from 28° to 32° is defined as being shared between the polar region and the intermediate region; a dimple having a centroid located at a latitude angle that is greater than 32° and less than 58° is defined as being within the intermediate region; a dimple having a centroid located at a latitude angle that is from 58° to 62° is defined as being shared between the intermediate region and the equatorial region; and a dimple having a centroid located at a latitude angle that is greater than 62° is defined as being within the equatorial region.

As discussed further below, for purposes of calculating the dimple surface coverage of a region, for dimples that are defined as being within either the polar region or the intermediate region or the equatorial region (i.e., dimples that are not defined as being shared between two regions), the entire area of the plan shape of the dimple is included in the calculation of the dimple surface coverage of the region in which the centroid of the dimple is located, even though a portion of the dimple may lie in another region. For dimples that are defined as being shared between either the polar and intermediate regions or the intermediate and equatorial regions, exactly one half of the entire area of the plan shape of the dimple is included in the calculation of the dimple surface coverage for each region sharing that dimple.

It should also be noted that, in embodiments of the present invention wherein the dimple pattern includes side edge dimples, when calculating the dimple surface coverage for the polar, intermediate, and equatorial regions of a single triangular section, only half of the total plan shape area for each side edge dimple is included in the calculation.

The polar region of each triangular section has a dimple surface coverage S_p , which, for purposes of the present

invention, is determined as follows. The surface area of the polar region of each triangular section (if no dimples were present), A_p , is calculated as:

$$A_p = \frac{2\pi R \cdot h_p}{4},$$

where R is the ball radius

$$R = \frac{\text{Ball Diameter}}{2},$$

and

$$h_p = R \left(1 - \cos\left(\frac{\pi}{6}\right)\right).$$

The sum of the plan shape areas of all of the dimples located in (i.e., having centroids located in) the polar region of each triangular section, AD_p , is calculated. The dimple surface coverage of the polar region of each triangular section, S_p , is then calculated as:

$$S_p = \frac{AD_p}{A_p} \times 100.$$

The intermediate region of each triangular section has a dimple surface coverage S_i , which, for purposes of the present invention, is determined as follows. The surface area of the intermediate region of each triangular section (if no dimples were present), A_i , is calculated as:

$$A_i = \frac{2\pi R \cdot h_i}{4} - A_p,$$

where R is the ball radius

$$R = \frac{\text{Ball Diameter}}{2},$$

$$h_i = R \left(1 - \cos\left(\frac{\pi}{3}\right)\right),$$

and A_p is the surface area of the polar region of each triangular section (if no dimples were present), calculated according to the equation above. The sum of the plan shape areas of all of the dimples located in (i.e., having centroids located in) the intermediate region of each triangular section, AD_i , is calculated. The dimple surface coverage of the intermediate region of each triangular section, S_i , is then calculated as:

$$S_i = \frac{AD_i}{A_i} \times 100.$$

The equatorial region of each triangular section has a dimple surface coverage S_e , which, for purposes of the present invention, is determined as follows. The surface area of the equatorial region of each triangular section (if no dimples were present), A_e , is calculated as:

$$A_e = \frac{2\pi R \cdot h_e}{4} - A_p - A_i,$$

10

where R is the ball radius

$$R = \frac{\text{Ball Diameter}}{2},$$

15

$$h_e = R \left(1 - \cos\left(\frac{\pi}{2}\right)\right),$$

and A_p and A_i are the surface area of the polar region of each triangular section (if no dimples were present) and the surface area of the intermediate region of each triangular section (if no dimples were present), respectively, calculated according to the equations above. The sum of the plan shape areas of all of the dimples located in (i.e., having centroids located in) the equatorial region of each triangular section, AD_e , is calculated. The dimple surface coverage of the equatorial region of each triangular section, S_e , is then calculated as:

$$S_e = \frac{AD_e}{A_e} \times 100.$$

In a particular embodiment, dimple patterns of the present invention have one or more of the following properties:

- 40 a) $S_p \neq S_i \neq S_e$;
  - b) $S_p < S_i < S_e$;
  - c) $S_i - S_p \geq 1$ or ≥ 4 or ≥ 7 ;
  - d) $S_e - S_i \geq 1$ or ≥ 4 or ≥ 7 ; and
  - e) $S_e - S_p \geq 5$ or ≥ 8 .
- 45 In another particular embodiment, dimple patterns of the present invention have one or more of the following properties:
- a) $S_i < S_p < S_e$;
  - b) $S_i \geq 70$;
  - c) $S_i \geq 75$; and
  - d) $S_i \geq 80$.

50 Each triangular section includes at least three different dimple diameters, including a maximum dimple diameter, a minimum dimple diameter, and at least one additional dimple diameter. In a particular embodiment, each triangular section includes at least four different dimple diameters. In another particular embodiment, each triangular section includes at least five different dimple diameters. In another particular embodiment, each triangular section includes at least six different dimple diameters. In a particular aspect of embodiments of the present invention wherein a polar dimple is present, the polar dimple does not have the minimum dimple diameter. In another particular aspect of embodiments of the present invention wherein a polar dimple is present, the polar dimple has the minimum dimple diameter. It should be understood that manufacturing variances are to be taken into account when determining the

number of different dimple diameters. For purposes of the present disclosure, dimples having substantially the same diameter, also referred to herein as "same diameter" dimples, includes dimples on a finished ball having respective diameters that differ by less than 0.005 inches due to manufacturing variances.

In a particular embodiment, dimple patterns of the present invention have one or more of the following properties:

- a) the polar region of each triangular section includes at least one dimple that has the minimum dimple diameter and is not a polar dimple, and, optionally, the latitude angle of at least one non-polar dimple located in the polar region and having the minimum dimple diameter is less than 20°;
- b) the polar region of each triangular section does not include a dimple having the maximum dimple diameter;
- c) the equatorial region of each triangular section includes at least one dimple having the maximum dimple diameter;
- d) the equatorial region of each triangular section does not include a dimple having the minimum dimple diameter;
- e) the intermediate region of each triangular section includes at least one dimple having the minimum dimple diameter; and
- f) the intermediate region of each triangular section includes at least one dimple having the maximum dimple diameter.

In another particular embodiment, dimple patterns of the present invention have one or more of the following properties:

- a) the polar region of each triangular section includes at least one dimple having the maximum dimple diameter;
- b) the intermediate region of each triangular section includes at least one dimple having the maximum dimple diameter;
- c) the equatorial region of each triangular section includes at least one dimple having the maximum dimple diameter;
- d) the polar region includes at least one dimple having the minimum dimple diameter, at least one dimple having the maximum dimple diameter, at least one dimple having a first additional diameter, at least one dimple having a second additional diameter, and, optionally, at least one dimple having a third additional diameter; and
- e) each triangular section includes a plurality of side edge dimples, and each of the plurality of side edge dimples has a diameter independently selected from the maximum dimple diameter and the greatest diameter of all of the additional dimple diameters present on the ball.

Dimple patterns of the present invention optionally have one or more of the following additional properties:

- a) the overall surface coverage of the golf ball is 75% or greater, or 78% or greater, or 80% or greater;
- b) there is a polar dimple;
- c) there is no polar dimple;
- d) each triangular section includes at least four, or at least five, different dimple diameters;
- e) within each triangular section, the number of different dimple diameters located in the intermediate region is greater than the number of different dimple diameters located in the polar region and greater than the number of different dimple diameters located in the equatorial region;
- f) within each triangular section, the number of different dimple diameters located in the polar region is equal to the number of different dimple diameters located in the equatorial region;

- g) the total number of dimples having the minimum dimple diameter is greater than the number of dimples having the maximum dimple diameter;
- h) the total number of dimples having the minimum dimple diameter is less than the number of dimples having the maximum dimple diameter;
- i) there are no dimple free great circles on the outer surface of the ball;
- j) the outer surface of the ball has a dimple free great circle corresponding to the equator; and
- k) the outer surface of the ball has a dimple free great circle corresponding to the equator and two dimple free great circles defined by the side edges of the triangular sections.

Dimples of the present invention are not limited to a particular plan shape or profile shape. Particularly suitable plan shapes include, but are not limited to, circular, polygonal, oval, and irregular shapes. Particularly suitable profile shapes include, but are not limited to, circular, catenary, elliptical, and conical shapes.

In a particular embodiment, dimple patterns of the present invention include a plurality of dimples having an elliptical plan shape. Elliptical plan shapes have a major axis and a minor axis, the length of the major axis being greater than the length of the minor axis. The length of the minor axis of elliptical plan shapes of dimples of the present invention is preferably, but not necessarily, from 0.120 inches to 0.160 inches. The difference between the length of the major axis and the length of the minor axis of elliptical plan shapes of dimples of the present invention is preferably, but not necessarily, 0.020 inches or less, or the difference is 0.003 inches or 0.005 inches or 0.020 inches, or the difference is within a range having a lower limit and an upper limit selected from these values. The difference between the length of the major axis and the length of the minor axis of an elliptical plan shape of one dimple may be the same as or different than that of an elliptical plan shape of another dimple. For example, the dimples having an elliptical plan shape may include a first portion of dimples wherein the difference between the length of the major axis and the length of the minor axis is from 0.003 inches to 0.005 inches, and a second portion of dimples wherein the difference between the length of the major axis and the length of the minor axis is from 0.005 inches to 0.020 inches. The ratio of the length of the major axis to the length of the minor axis of elliptical plan shapes of dimples of the present invention is preferably, but not necessarily, from 1.02 to 1.10, or from 1.02 to 1.04, or from 1.04 to 1.10. The ratio of the length of the major axis to the length of the minor axis of an elliptical plan shape of one dimple may be the same as or different than that of an elliptical plan shape of another dimple. For example, the dimples having an elliptical plan shape may include a first portion of dimples wherein the ratio of the length of the major axis to the length of the minor axis is from 1.02 to 1.04, and a second portion of dimples wherein the ratio of the length of the major axis to the length of the minor axis is from 1.04 to 1.10.

In a particular aspect of this embodiment, at least 2%, or from 2% to 10%, or from 4% to 8%, of the dimples have an elliptical plan shape. In a further particular aspect of this embodiment, the remaining dimples consist of dimples having a circular plan shape. In another further particular aspect of this embodiment, the remaining dimples consist of dimples having a non-elliptical, non-circular plan shape. In another further particular aspect of this embodiment, the remaining dimples include a first portion of dimples having

11

a circular plan shape and a second portion of dimples having a non-elliptical, non-circular plan shape.

In another particular aspect of this embodiment, each dimple having an elliptical plan shape is located in the polar region. In a further particular aspect of this embodiment, the polar dimple, if present, has a circular plan shape.

Each dimple on the outer surface of the ball preferably has a diameter of 0.050 or 0.060 or 0.070 or 0.080 or 0.090 or 0.100 or 0.110 or 0.120 or 0.130 or 0.150 or 0.160 or 0.170 or 0.180 or 0.190 or 0.200 or 0.205 or 0.210 or 0.220 or 0.250 inches or a diameter within a range having a lower limit and an upper limit selected from these values. In a particular embodiment, the maximum difference between any two dimple diameters on the ball is less than 0.055 inches. The diameter of a dimple having a non-circular plan shape is defined by its equivalent diameter, d_e , which is calculated as:

$$d_e = 2\sqrt{\frac{A}{\pi}}$$

where A is the plan shape area of the dimple. By the term, "plan shape area," it is meant the area based on a planar view of the dimple plan shape, such that the viewing plane is normal to an axis connecting the center of the golf ball to the centroid of the dimple. Diameter measurements are determined on finished golf balls according to FIG. 3. Generally, it may be difficult to measure a dimple's diameter due to the indistinct nature of the boundary dividing the dimple from the ball's undisturbed land surface. Due to the effect of paint and/or the dimple design itself, the junction between the land surface and dimple may not be a sharp corner and is therefore indistinct. This can make the measurement of a dimple's diameter somewhat ambiguous. To resolve this problem, dimple diameter on a finished golf ball is measured according to the method shown in FIG. 3. FIG. 3 shows a dimple half-profile 34, extending from the dimple centerline 31 to the land surface outside of the dimple 33. A ball phantom surface 32 is constructed above the dimple as a continuation of the land surface 33. A first tangent line T1 is then constructed at a point on the dimple sidewall that is spaced 0.003 inches radially inward from the phantom surface 32. T1 intersects phantom surface 32 at a point P1, which defines a nominal dimple edge position. A second tangent line T2 is then constructed, tangent to the phantom surface 32, at P1. The edge angle is the angle between T1 and T2. The dimple diameter is the distance between P1 and its equivalent point diametrically opposite along the dimple perimeter. Alternatively, it is twice the distance between P1 and the dimple centerline 31, measured in a direction perpendicular to centerline 31. The dimple depth is the distance measured along a ball radius from the phantom surface of the ball to the deepest point on the dimple. The dimple volume is the space enclosed between the phantom surface 32 and the dimple surface 34 (extended along T1 until it intersects the phantom surface).

In a particular embodiment, a majority of the dimples on the outer surface of golf balls of the present invention are spherical dimples, i.e., dimples having a circular plan shape and a profile shape based on a spherical function.

In a particular aspect of this embodiment, the spherical dimples have one or more properties/characteristics selected from:

12

- a) the edge angle of each spherical dimple is 10° or 11° or 12° or 13° or 14° or 15° or 16°, or is within a range having a lower limit and an upper limit selected from these values;
- b) the maximum difference in edge angle between any two of the spherical dimples is 1°; and
- c) the edge angle of all of the spherical dimples is substantially the same (For purposes of the present disclosure, edge angles on a finished ball are substantially the same if they differ by less than 0.25°).

In another particular aspect of this embodiment, the spherical dimples have one or more properties/characteristics selected from.

- a) the edge angle of each spherical dimple is 10° or 11° or 12° or 13° or 14° or 15° or 16°, or is within a range having a lower limit and an upper limit selected from these values;
- b) the difference in the average edge angle of the spherical dimples present in the polar region and the average edge angle of the spherical dimples present in the intermediate region is greater than 0.25°, or greater than 0.50°;
- c) the difference in the average edge angle of the spherical dimples present in the intermediate region and the average edge angle of the spherical dimples present in the equatorial region is greater than 0.25°, or greater than 0.50°; d) the difference in the average edge angle of the spherical dimples present in the polar region and the average edge angle of the spherical dimples present in the equatorial region is greater than 0.25°, or greater than 0.50°;
- e) the average edge angle of the spherical dimples present in the polar region is less than the average edge angle of the spherical dimples present in the intermediate region;
- f) the average edge angle of the spherical dimples present in the intermediate region is less than the average edge angle of the spherical dimples present in the equatorial region;
- g) the average edge angle of the spherical dimples present in the polar region is greater than the average edge angle of the spherical dimples present in the intermediate region;
- h) the average edge angle of the spherical dimples present in the intermediate region is greater than the average edge angle of the spherical dimples present in the equatorial region;
- i) the spherical dimples present in the polar region have substantially the same edge angle;
- j) the spherical dimples present in the intermediate region have substantially the same edge angle;
- k) the spherical dimples present in the equatorial region have substantially the same edge angle;
- l) the spherical dimples present in the polar region include dimples having at least two different edge angles;
- m) the spherical dimples present in the intermediate region include dimples having at least two different edge angles; and
- n) the spherical dimples present in the equatorial region include dimples having at least two different edge angles.

Preferably, none of the dimples on the outer surface of the ball overlap or touch.

Dimple patterns generated by the present invention are capable of achieving a high percentage of surface coverage. In a particular embodiment, the present invention generates a surface coverage of about 75% or greater. In another

particular embodiment, the present invention generates a surface coverage of about 78% or greater.

The total number of dimples on the golf ball is preferably an even number between about 250 and about 500. In a particular embodiment, the total number of dimples is 320 or 322 or 328 or 330 or 336 or 338 or 344 or 346 or 352 or 354 or 360 or 362 or 368 or 370 or the total number of dimples is within a range having a lower limit and an upper limit selected from these values.

Golf balls of the present invention are not limited by a particular golf ball construction. The golf ball may have any type of core, such as solid, liquid, wound, and the like, and may be a one-piece, two-piece, or multilayer ball. Each layer of the golf ball may be constructed from any suitable thermoset or thermoplastic material known to those of ordinary skill in the art. When desirable, the cover may be coated with any number of layers, such as a base coat, top coat, paint, or any other desired coating. As will be appreciated by those skilled in the art, any manufacturing technique may be used to construct the various portions of the golf ball. In a particular embodiment, the golf ball is a multilayer ball comprising a solid, single layer core, an inner cover layer, and an outer cover layer. In a particular aspect of this embodiment, the core is formed from a thermoset rubber, the inner cover layer is formed from an ionomer composition, and the outer cover layer is formed from a polyurethane composition.

EXAMPLES

The following non-limiting examples demonstrate dimple patterns of golf balls made in accordance with the present invention. The examples are merely illustrative of the preferred embodiments of the present invention, and are not to be construed as limiting the invention, the scope of which is defined by the appended claims.

Non-limiting Exemplary Dimple Pattern 1

A triangular section of a dimple pattern based on a square dipyramid according to a particular embodiment of the present invention is illustrated in FIGS. 4A-4C. FIGS. 4A-4C show a triangular dimple section 10 packed with dimples into a dimple arrangement consisting of: thirty-two non-intersecting dimples, one polar dimple, ten side edge dimples, and six non-shared equatorial dimples. Thus, a golf ball having a dimple pattern based on a square dipyramid, with each triangular dimple section having the dimple arrangement shown in FIGS. 4A-4C, has a total of 346 dimples, with a surface coverage of about 82.1%. The golf ball has a non-planar parting line that is defined by a drawing a non-linear segment 11 along the path of each equatorial edge. To provide for dimples in the pattern whose perimeters are intersected by an equatorial edge, the dimple pattern has a rotational offset between the two hemispheres of about 45°. There are no dimple free great circles on the outer surface of the ball.

In FIGS. 4A-4B, the numerical labels within the dimples designate same diameter dimples; i.e., all dimples labelled 1 have substantially the same diameter, all dimples labelled 2 have substantially the same diameter, and so on. In a particular aspect of the embodiment illustrated in FIGS. 4A-4C, same diameter dimples also have substantially the same chord depth and substantially the same edge angle. In a further particular aspect of the embodiment illustrated in FIGS. 4A-4C, the dimples labelled 1-5 have the diameters given in Table 1 below:

TABLE 1

Numerical Label	Dimple Diameter (inches)
1	0.128
2	0.150
3	0.160
4	0.170
5	0.180

Thus, according to the embodiment shown in FIGS. 4A-4B, and wherein the dimples have properties according to Table 1, the dimples have a total of five different dimple diameters, including a minimum dimple diameter of 0.128 inches and a maximum dimple diameter of 0.180. The total number of dimples on the ball having the minimum dimple diameter is forty, and the total number of dimples on the ball having the maximum dimple diameter is sixty-four.

FIGS. 4B & 4C show lines drawn at latitude angle 30° and 20 latitude angle 60°, thereby dividing the triangular dimple section 10 into a polar region 15, an intermediate region 17, and an equatorial region 19. In FIG. 4C, the alphabetical labels within the dimples designate the region in which the dimple is located; i.e., all dimples labelled A are located in the polar region 15, all dimples labelled B are located in the intermediate region 17, and all dimples labelled C are located in the equatorial region 19.

Thus, according to the embodiment shown in FIGS. 4A-4C, and wherein the dimples have properties according to Table 1, the triangular dimple section 10 has the following properties:

- the polar region 15 includes one dimple that has the minimum dimple diameter, the latitude angle of which is about 15°;
- the polar region 15 does not include a dimple having the maximum dimple diameter;
- the intermediate region 17 includes four dimples having the minimum dimple diameter;
- the intermediate region 17 includes two dimples having the maximum dimple diameter;
- the equatorial region 19 includes eight dimples having the maximum dimple diameter, including four non-shared equatorial dimples and four side edge dimples;
- the equatorial region 19 does not include a dimple having the minimum dimple diameter;
- the intermediate region 17 includes five different dimple diameters, the polar region 15 includes three different diameters, and the equatorial region 19 includes three different diameters; thus, the number of different dimple diameters located in the intermediate region 17 is greater than the number of different dimple diameters located in the polar region 15 and greater than the number of different dimple diameters located in the equatorial region 19, and the number of different dimple diameters located in the polar region 15 is equal to the number of different dimple diameters located in the equatorial region 19; and
- the polar region 15 has a surface coverage S_p of 69.4%;
- the intermediate region 17 has a surface coverage S_i of 79.2%; and
- the equatorial region 19 has a surface coverage S_e 87.1%.

Non-Limiting Exemplary Dimple Pattern 2

A triangular section of a dimple pattern based on a square dipyramid according to a particular embodiment of the present invention is illustrated in FIGS. 5A-5C. FIGS. 5A-5C show a triangular dimple section 10 packed with

15

dimples into a dimple arrangement consisting of: thirty-two non-intersecting dimples, one polar dimple, ten side edge dimples, and six non-shared equatorial dimples. Thus, a golf ball having a dimple pattern based on a square dipyramid, with each triangular dimple section having the dimple arrangement shown in FIGS. 5A-5C, has a total of 346 dimples, with a surface coverage of about 80.3%. The golf ball has a non-planar parting line that is defined by a drawing a non-linear segment 11 along the path of each equatorial edge. To provide for dimples in the pattern whose perimeters are intersected by an equatorial edge, the dimple pattern has a rotational offset between the two hemispheres of about 45°. There are no dimple free great circles on the outer surface of the ball.

In FIGS. 5A-5B, the numerical labels within the dimples designate same diameter dimples; i.e., all dimples labelled 1 have substantially the same diameter, all dimples labelled 2 have substantially the same diameter, and so on.

In a particular aspect of the embodiment illustrated in FIGS. 5A-5C, same diameter dimples also have substantially the same chord depth and substantially the same edge angle.

In a further particular aspect of the embodiment illustrated in FIGS. 5A-5C, the dimples labelled 1-5 have the diameters given in Table 2 below, all of the dimples having substantially the same chord depth and substantially the same edge angle.

TABLE 2

Numerical Label	Dimple Diameter (inches)
1	0.128
2	0.150
3	0.160
4	0.170
5	0.180

In an alternative particular aspect of the embodiment illustrated in FIGS. 5A-5C, same diameter dimples located in different regions do not have the same edge angle. Thus, in a further particular aspect of the embodiment shown in FIGS. 5A-5C, the dimples labelled 1-5 have the diameters and edge angles given in Table 3 below.

TABLE 3

Region	Numerical Label	Dimple Diameter (inches)	Edge Angle (°)
polar	1	0.128	13.00
polar	2	0.150	13.00
polar	3	0.160	13.00
intermediate	1	0.128	13.50
intermediate	2	0.150	13.50
intermediate	3	0.160	13.50
intermediate	4	0.170	13.50
equatorial	3	0.160	14.00
equatorial	4	0.170	14.00
equatorial	5	0.180	14.00

average edge angle of dimples of polar region 13.00°

average edge angle of dimples of intermediate region 13.50°

average edge angle of dimples of equatorial region 14.00°

In another further particular aspect of the embodiment shown in FIGS. 5A-5C, the dimples labelled 1-5 have the diameters and edge angles given in Table 4 below.

16

TABLE 4

Region	Numerical Label	Dimple Diameter (inches)	Edge Angle (°)
polar	1	0.128	13.00
polar	2	0.150	13.30
polar	3	0.160	13.30
intermediate	1	0.128	13.50
intermediate	2	0.150	13.80
intermediate	3	0.160	14.20
intermediate	4	0.170	14.20
equatorial	3	0.160	14.00
equatorial	4	0.170	14.30
equatorial	5	0.180	14.60

average edge angle of dimples of polar region 13.24°

average edge angle of dimples of intermediate region 13.89°

average edge angle of dimples of equatorial region 14.36°

Thus, according to the embodiment shown in FIGS. 5A-5B, and wherein the dimples have properties according to Table 2 or Table 3 or Table 4, the dimples have a total of five different dimple diameters, including a minimum dimple diameter of 0.128 inches and a maximum dimple diameter of 0.180. The total number of dimples on the ball having the minimum dimple diameter is forty, and the total number of dimples on the ball having the maximum dimple diameter is sixty-four.

FIGS. 5B & 5C show lines drawn at latitude angle 30° and latitude angle 60°, thereby dividing the triangular dimple section 10 into a polar region 15, an intermediate region 17, and an equatorial region 19. In FIG. 5C, the alphabetical labels within the dimples designate the region in which the dimple is located; i.e., all dimples labelled A are located in the polar region 15, all dimples labelled B are located in the intermediate region 17, and all dimples labelled C are located in the equatorial region 19.

Thus, according to the embodiment shown in FIGS. 5A-5C, and wherein the dimples have properties according to Table 2 or Table 3 or Table 4, the triangular dimple section 10 has the following properties:

- the polar region 15 includes one dimple that has the minimum dimple diameter, the latitude angle of which is about 15°;
- the polar region 15 does not include a dimple having the maximum dimple diameter;
- the intermediate region 17 includes four dimples having the minimum dimple diameter;
- the intermediate region 17 does not include a dimple having the maximum dimple diameter;
- the equatorial region 19 includes ten dimples having the maximum dimple diameter, including six non-shared equatorial dimples and four side edge dimples;
- the equatorial region 19 does not include a dimple having the minimum dimple diameter;
- the intermediate region 17 includes four different dimple diameters, the polar region 15 includes three different diameters, and the equatorial region 19 includes three different diameters; thus, the number of different dimple diameters located in the intermediate region 17 is greater than the number of different dimple diameters located in the polar region 15 and greater than the number of different dimple diameters located in the equatorial region 19, and the number of different dimple diameters located in the polar region 15 is equal to the number of different dimple diameters located in the equatorial region 19;
- the polar region 15 has a surface coverage S_p of 64.2%;

- i) the intermediate region **17** has a surface coverage S_i of 74.8%; and
j) the equatorial region **19** has a surface coverage S_e of 88.1%.

Non-Limiting Exemplar Dimple Pattern 3

A triangular section of a dimple pattern based on a square dipyramid according to a particular embodiment of the present invention is illustrated in FIGS. **6A-6B**. FIGS. **6A-6B** show a triangular dimple section **10** packed with dimples into a dimple arrangement consisting of: thirty-two non-intersecting dimples, one polar dimple, ten side edge dimples, and six non-shared equatorial dimples. Thus, a golf ball having a dimple pattern based on a square dipyramid, with each triangular dimple section having the dimple arrangement shown in FIGS. **6A-6B**, has a total of 346 dimples, with a surface coverage of about 81.0%. The golf ball has a non-planar parting line that is defined by a drawing a non-linear segment **11** along the path of each equatorial edge. To provide for dimples in the pattern whose perimeters are intersected by an equatorial edge, the dimple pattern has a rotational offset between the two hemispheres of about 45°. There are no dimple free great circles on the outer surface of the ball.

In FIGS. **6A-6B**, the dimples having a numerical label have a circular plan shape, and the numerical labels within the dimples designate same diameter dimples; i.e., all dimples labelled 1 have substantially the same diameter, all dimples labelled 2 have substantially the same diameter, and so on. In a particular aspect of the embodiment illustrated in FIGS. **6A-6B**, the dimples labelled 1-6 have the diameters given in Table 5 below:

TABLE 5

Numerical Label	Dimple Diameter (inches)
1	0.128
2	0.150
3	0.160
4	0.170
5	0.175
6	0.180

In FIGS. **6A-6B**, the dimples having an alphanumerical label have an elliptical plan shape, and the alphanumerical labels within the dimples designate dimples having major and minor axes of substantially the same length; i.e., all dimples labelled N1 have substantially the same length major axis and substantially the same length minor axis, all dimples labelled N2 have substantially the same length major axis and substantially the same length minor axis, and so on. In a particular aspect of the embodiment illustrated in FIGS. **6A-6B**, the dimples labelled N1 and N2 have the properties given in Table 6 below:

TABLE 6

Alphanumerical Label	Minor Axis Length (inches)	Major Axis Length (inches)
N1	0.123	0.127
N2	0.150	0.163

Thus, according to the embodiment shown in FIGS. **6A-6B**, and wherein the dimples have properties according to Tables 5 and 6, the dimples include circular plan shaped dimples having a total of six different dimple diameters, including a minimum dimple diameter of 0.128 inches and

a maximum dimple diameter of 0.180, and elliptical plan shaped dimples of a first type N1 and a second type N2, the first type N1 having a difference between the length of the major axis and the length of the minor axis of 0.004 inches and a ratio of the length of the major axis to the length of the minor axis of 1.03, and the second type N2 having a difference between the length of the major axis and the length of the minor axis of 0.013 inches and a ratio of the length of the major axis to the length of the minor axis of 1.09.

FIG. **6B** shows lines drawn at latitude angle 30° and longitude angle 60°, thereby dividing the triangular dimple section **10** into a polar region **15**, an intermediate region **17**, and an equatorial region **19**. As shown in FIG. **6B**, each dimple having an elliptical plan shape is located in the polar region **15**. Additionally, according to the embodiment shown in FIGS. **6A-6B**, and wherein the dimples have properties according to Tables 5 and 6, the triangular dimple section **10** has the following properties:

- a) the polar region **15** has a surface coverage S_p of 70.0%;
b) the intermediate region **17** has a surface coverage S_i of 79.2%; and
c) the equatorial region **19** has a surface coverage S_e of 85.4%.

Non-Limiting Exemplar Dimple Pattern 4

A triangular section of a dimple pattern based on a square dipyramid according to a particular embodiment of the present invention is illustrated in FIG. **7**. FIG. **7** shows a triangular dimple section **10** packed with dimples into a dimple arrangement consisting of: twenty-seven non-intersecting dimples, one polar dimple, ten side edge dimples, six shared equatorial dimples and two base vertex dimples. Thus, a golf ball having a dimple pattern based on a square dipyramid, with each triangular dimple section having the dimple arrangement shown in FIG. **7**, has a total of 314 dimples, with a surface coverage of about 78.6%. The golf ball has a non-planar parting line that is defined by a drawing a non-linear segment **11** along the path of each equatorial edge. To provide for dimples in the pattern whose perimeters are intersected by an equatorial edge, the dimple pattern has a rotational offset between the two hemispheres of about 45°. There are no dimple free great circles on the outer surface of the ball.

In FIG. **7**, the numerical labels within the dimples designate same diameter dimples; i.e., all dimples labelled 1 have substantially the same diameter, all dimples labelled 2 have substantially the same diameter, and so on. In a particular aspect of the embodiment illustrated in FIG. **7**, same diameter dimples also have substantially the same chord depth and substantially the same edge angle. In another particular aspect of the embodiment illustrated in FIG. **7**, the dimples labelled 1-5 have the diameters given in Table 7 below:

TABLE 7

Numerical Label	Dimple Diameter (inches)
1	0.130
2	0.140
3	0.150
4	0.160
5	0.170

FIG. **7** shows lines drawn at latitude angle 30° and longitude angle 60°, thereby dividing the triangular dimple section **10** into a polar region **15**, an intermediate region **17**, and an

equatorial region 19. Each of three dimples 21 has a centroid that lies at a latitude angle of from 28° to 32°; thus, the three dimples 21 are shared between the polar region 15 and the intermediate region 17.

The polar region 15 has a surface coverage S_p of 76.6%. The intermediate region 17 has a surface coverage S_i of 73.4%. The equatorial region 19 has a surface coverage S_e 83.3%.

Non-limiting Exemplary Dimple Pattern 5

A triangular section of a dimple pattern based on a square dipyramid according to a particular embodiment of the present invention is illustrated in FIG. 8. FIG. 8 shows a triangular dimple section 10 packed with dimples into a dimple arrangement consisting of: thirty-one non-intersecting dimples, one polar dimple, eight side edge dimples, six shared equatorial dimples and two base vertex dimples. Thus, a golf ball having a dimple pattern based on a square dipyramid, with each triangular dimple section having the dimple arrangement shown in FIG. 8, has a total of 338 dimples, with a surface coverage of about 79.2%. The golf ball has a non-planar parting line that is defined by a drawing a non-linear segment 11 along the path of each equatorial edge. To provide for dimples in the pattern whose perimeters are intersected by an equatorial edge, the dimple pattern has a rotational offset between the two hemispheres of about 45°. There are no dimple free great circles on the outer surface of the ball.

In FIG. 8, the numerical labels within the dimples designate same diameter dimples; i.e., all dimples labelled 1 have substantially the same diameter, all dimples labelled 2 have substantially the same diameter, and so on. In a particular aspect of the embodiment illustrated in FIG. 8, same diameter dimples also have substantially the same chord depth and substantially the same edge angle. In another particular aspect of the embodiment illustrated in FIG. 8, the dimples labelled 1-6 have the diameters given in Table 8 below:

TABLE 8

Numerical Label	Dimple Diameter (inches)
1	0.100
2	0.110
3	0.125
4	0.140
5	0.155
6	0.170
7	0.190

FIG. 8 shows lines drawn at latitude angle 30° and latitude angle 60°, thereby dividing the triangular dimple section 10 into a polar region 15, an intermediate region 17, and an equatorial region 19. Each of three dimples 21 has a centroid that lies at a latitude angle of from 28° to 32°; thus, the three dimples 21 are shared between the polar region 15 and the intermediate region 17.

The polar region 15 has a surface coverage S_p of 80.2%. The intermediate region 17 has a surface coverage S_i of 73.4%. The equatorial region 19 has a surface coverage S_e 83.6%.

Non-Limiting Exemplary Dimple Pattern 6

A triangular section of a dimple pattern based on a square dipyramid according to a particular embodiment of the present invention is illustrated in FIG. 9. FIG. 9 shows a triangular dimple section 10 packed with dimples into a dimple arrangement consisting of: thirty-five non-intersecting dimples, one polar dimple, twelve side edge dimples,

and seven shared equatorial dimples. Thus, a golf ball having a dimple pattern based on a square dipyramid, with each triangular dimple section having the dimple arrangement shown in FIG. 9, has a total of 386 dimples, with a surface coverage of about 82.6%. The golf ball has a non-planar parting line that is defined by a drawing a non-linear segment 11 along the path of each equatorial edge. To provide for dimples in the pattern whose perimeters are intersected by an equatorial edge, the dimple pattern has a rotational offset between the two hemispheres of about 45°. There are no dimple free great circles on the outer surface of the ball.

In FIG. 9, the numerical labels within the dimples designate same diameter dimples; i.e., all dimples labelled 1 have substantially the same diameter, all dimples labelled 2 have substantially the same diameter, and so on. In a particular aspect of the embodiment illustrated in FIG. 9, same diameter dimples also have substantially the same chord depth and substantially the same edge angle. In another particular aspect of the embodiment illustrated in FIG. 9, the dimples labelled 1-7 have the diameters given in Table 9 below:

TABLE 9

Numerical Label	Dimple Diameter (inches)
1	0.100
2	0.110
3	0.125
4	0.140
5	0.155
6	0.170
7	0.190

FIG. 9 shows lines drawn at latitude angle 30° and latitude angle 60°, thereby dividing the triangular dimple section 10 into a polar region 15, an intermediate region 17, and an equatorial region 19. Each of five dimples 21 has a centroid that lies at a latitude angle of from 28° to 32°; thus, the five dimples 21 are shared between the polar region 15 and the intermediate region 17. Each of three dimples 23 has a centroid that lies at a latitude angle of from 58° to 62°, thus, the three dimples 23 are shared between the intermediate region 17 and the equatorial region 19.

The polar region 15 has a surface coverage S_p of 83.4%. The intermediate region 17 has a surface coverage S_i of 80.2%. The equatorial region 19 has a surface coverage S_e 84.6%.

When numerical lower limits and numerical upper limits are set forth herein, it is contemplated that any combination of these values may be used.

All patents, publications, test procedures, and other references cited herein, including priority documents, are fully incorporated by reference to the extent such disclosure is not inconsistent with this invention and for all jurisdictions in which such incorporation is permitted.

While the illustrative embodiments of the invention have been described with particularity, it will be understood that various other modifications will be apparent to and can be readily made by those of ordinary skill in the art without departing from the spirit and scope of the invention. Accordingly, it is not intended that the scope of the claims appended hereto be limited to the examples and descriptions set forth herein, but rather that the claims be construed as encompassing all of the features of patentable novelty which reside in the present invention, including all features which would

21

be treated as equivalents thereof by those of ordinary skill in the art to which the invention pertains.

What is claimed is:

1. A golf ball having a plurality of dimples disposed on the spherical outer surface thereof, wherein:

the plurality of dimples comprises at least three different dimple diameters, including a minimum dimple diameter, a maximum dimple diameter, and at least one additional dimple diameter;

the golf ball consists of two hemispheres separated by an equator, the two hemispheres having substantially identical dimple arrangements;

each hemispherical dimple arrangement consists of four triangular sections that are defined by projecting the four faces of a square pyramid onto the hemisphere such that each of the four triangular sections is defined by a border consisting of a linear equatorial edge which corresponds to a portion of the equator of the ball and two linear side edges connecting each end of the equatorial edge to a pole of the ball;

the four triangular sections of each hemisphere are substantially identical in size and dimple arrangement;

the dimple arrangement within each of the four triangular sections optionally includes a shared polar dimple having a centroid that lies at the vertex of the two side edges of the section;

the dimple arrangement within each of the four triangular sections is not rotationally symmetric about the center of the section;

each of the four triangular sections can be divided into a polar region from latitude angle 0° to latitude angle 30° , an intermediate region from latitude angle 30° to latitude angle 60° , and an equatorial region from latitude angle 60° to latitude angle 90° , where latitude angle 0° is the pole and latitude angle 90° is the equator;

each of the polar region, the intermediate region, and the equatorial region includes at least one dimple having the maximum dimple diameter;

the polar region has a dimple surface coverage S_p , the intermediate region has a dimple surface coverage S_i , the equatorial region has a dimple surface coverage S_e , and $S_i < S_p < S_e$.

2. The golf ball of claim 1, wherein the plurality of dimples comprises at least four different dimple diameters, including the minimum dimple diameter, the maximum dimple diameter, a first additional dimple diameter, and a second additional dimple diameter; and wherein the polar region includes at least one dimple having the minimum dimple diameter, at least one dimple having the maximum dimple diameter, at least one dimple having the first additional dimple diameter, and at least one dimple having the second dimple diameter.

3. The golf ball of claim 1, wherein the plurality of dimples comprises at least five different dimple diameters, including the minimum dimple diameter, the maximum dimple diameter, a first additional dimple diameter, a second additional dimple diameter, and a third additional dimple diameter; and wherein the polar region includes at least one dimple having the minimum dimple diameter, at least one dimple having the maximum dimple diameter, at least one dimple having the first additional dimple diameter, at least one dimple having the second dimple diameter, and at least one dimple having the third dimple diameter.

4. The golf ball of claim 1, wherein the dimple arrangement within each of the four triangular sections includes a plurality of side edge dimples, each side edge dimple having

22

a centroid that lies on a linear side edge; and wherein each of the plurality of side edge dimples has a diameter independently selected from the maximum dimple diameter and the greatest diameter of all of the additional dimple diameters.

5. The golf ball of claim 1, wherein the dimple arrangement within each of the four triangular sections has mirror symmetry over a plane that intersects the polar axis and the midpoint of the linear equatorial edge of the dimple section; and wherein the centroid of at least one non-polar dimple lies on the plane of mirror symmetry.

6. The golf ball of claim 5, wherein each non-polar dimple whose centroid lies on the plane of mirror symmetry has a diameter independently selected from the maximum dimple diameter and the greatest diameter of all of the additional diameters.

7. The golf ball of claim 5, wherein each non-polar dimple whose centroid lies on the plane of mirror symmetry has the maximum dimple diameter.

8. The golf ball of claim 1, wherein each of at least two of the polar region, the intermediate region, and the equatorial region includes at least one dimple having the minimum dimple diameter.

9. The golf ball of claim 1, wherein each of the polar region, the intermediate region, and the equatorial region includes at least one dimple having the minimum dimple diameter.

10. The golf ball of claim 1, wherein the dimple arrangement includes the shared polar dimple.

11. The golf ball of claim 10, wherein the shared polar dimple has the minimum dimple diameter.

12. The golf ball of claim 1, wherein the dimple arrangement within each of the four triangular sections includes at least three dimples that are shared between regions such that the centroid of each dimple shared between regions is located at a latitude angle independently selected from latitude angles of from 28° to 32° and from 58° to 62° .

13. The golf ball of claim 1, wherein the dimple arrangement within each of the four triangular sections includes at least five dimples that are shared between regions such that the centroid of each dimple shared between regions is located at a latitude angle independently selected from latitude angles of from 28° to 32° and from 58° to 62° .

14. The golf ball of claim 1, wherein the dimple arrangement within each of the four triangular sections includes at least three dimples that are shared between the polar region and the intermediate region such that the centroid of each dimple shared between the polar region and the intermediate region is located at a latitude angle independently selected from latitude angles of from 28° to 32° .

15. The golf ball of claim 1, wherein the dimple arrangement within each of the four triangular sections includes at least five dimples that are shared between the polar region and the intermediate region such that the centroid of each dimple shared between the polar region and the intermediate region is located at a latitude angle independently selected from latitude angles of from 28° to 32° .

16. The golf ball of claim 15, wherein the dimple arrangement within each of the four triangular sections includes at least three dimples that are shared between the intermediate region and the equatorial region such that the centroid of each dimple shared between the intermediate region and the equatorial region is located at a latitude angle independently selected from latitude angles of from 58° to 62° .

- 17.** The golf ball of claim **1**, wherein $S_i \geq 70$.
- 18.** The golf ball of claim **1**, wherein $S_i \geq 75$.
- 19.** The golf ball of claim **1**, wherein $S_i \geq 80$.
